UNITED STATES PATENT OFFICE.

CARRIE STERNBERG, OF PHILADELPHIA, PENNSYLVANIA.

DESIGN FOR A CANDLE STAND.

Application filed January 21, 1928. Serial No. 24,964. Term of patent 14 years.

To all whom it may concern:

Be it known that I, CARRIE STERNBERG, a citizen of the United States, residing at Philadelphia, in the county of Philadelphia and State of Pennsylvania, have invented a new, original, and ornamental Design for Candle Stands, of which the following is a specification, reference being had to the accompanying drawing, forming part thereof.

The figure is a perspective view of a candle stand, showing my new design.

I claim:

The ornamental design for a candle stand, as shown.

CARRIE STERNBERG.
